UNITED STATES PATENT OFFICE.

PIETER DE LANGE AND ROBERT AERNOUT BARON VAN LYNDEN, OF Utrecht, NETHERLANDS, ASSIGNORS TO NAAMLOCHE VENNOOTSCHAP DE NEDERLANDSCHE THERMO-TELEFOON MAATSCHAPPIJ, OF Utrecht, NETHERLANDS, A CORPORATION OF NETHERLANDS.

THERMIC TELEPHONE.

1,200,471.

Specification of Letters Patent.

Patented Oct. 10, 1916.

Application filed November 4, 1915. Serial No. 59,626.

To all whom it may concern:

Be it known that we, PIETER DE LANGE and ROBERT AERNOUT BARON VAN LYNDEN, both subjects of the Queen of the Netherlands, and residing at Utrecht, in the Netherlands, have invented new and useful Improvements in Thermic Telephones, of which the following is a specification.

Our invention relates to thermic telephones, and its object is to improve the sound reproduction in such telephones.

Experiments have shown that in thermic telephones a perfect reproduction of the sound, and particularly of sibilant and labial sounds, can only be attained when the volume of the sounding chamber of the thermic telephone is accurately tuned to suit the heating conductors disposed in it. According to our invention this result is obtained in a simple and yet very efficient manner by arranging in the sound chamber an insertion partly filling up the space therein. The tuning of the sounding chamber corresponds to the shape and dimensions of said insertion, and with an insertion of suitable form and size, the sounding chamber may be so tuned as to adapt itself to the action of the heating conductors. Preferably, the insertion is made exchangeable and of a good conductor of heat so as to enable it to rapidly discharge the heat from the sounding chamber, which has a favorable effect on the reproduction of sound. The insertion body may be so formed and arranged in the sounding chamber that it covers the opening of the sounding chamber, thus protecting the heat wires in said chamber from outside influences. The insertion body may also be utilized for firmly connecting and supporting the parts constituting the thermic telephone.

Reference is to be had to the accompanying drawings in which our invention is illustrated by way of example.

Figure 1 is an elevation, partly in section, of a thermic telephone according to this invention, Fig. 2 shows the insertion in elevation, and Fig. 3 in plan view.

Referring to Fig. 1, the thermic telephone comprises a cylindrical support 2 of insulating material for the heating conductors 1. This support is mounted in the lower

portion of a hood 4 forming the sounding chamber 3 and having a sound opening 11 at the top, and rests against a shoulder 5 55 provided in the inner wall of said hood. The support 2 is held in position by means of a plug 9 screwed into the open end of hood 4. The branches of the arched heating conductors 1 are passed with their ends 60 through the support 2 and are bent so as to form feet 6 which lie against the lower face of the support 2. These feet are engaged by the similarly bent ends 7 of current conductors 8' fixed in plug 9. These conductors have eyes at their free ends to which the conductor wires 8 may be connected. A bore 10 in plug 9 permits the passage of said conductor wires.

Between the support 2 for the heating 70 conductors 1 and the top of hood 4 is interchangeably arranged an insertion 12, Figs. 2 and 3, widened at the top so as to resemble a mushroom. The stem of the insertion is preferably rounded at its base 13 and rests 75 in a correspondingly shaped central recess 14 of the support 2. The mushroom-shaped upper portion of the insertion body engages the inner arch of the hood 4, so that the sound opening 11 is covered by it so as to 80 prevent any damage to the heating conductors. The necessary communication between the sound chamber 3 and the sound opening 11 is established through radial grooves 15 in the mushroom head which open into a 85 central recess 16 opposite the sound opening 11 in the hood 4. On the parts 4, 2 and 9 being assembled, the insertion body forms a connection between the support 2 and the hood 4 which contributes to strengthening 90 the construction of the telephone. By selecting an insertion of suitable size and shape, the volume of the sound chamber 3 may be accurately tuned to conform to the action of the heating conductors 1. As the 95 insertion is made of a material which is a good conductor of heat, such as metal it assists the rapid discharge of heat from the sound chamber 3, which, as proved by experience, considerably improves the sound re- 100 production.

It is obvious that our invention is not limited to the precise form of the insertion 12 illustrated in the drawings; modifications

may be made in various respects according to circumstances without departing from the spirit of our invention.

We claim:

- 5 1. In a thermic telephone, a sounding chamber, having a sound opening, heating conductors in said sounding chamber, a support for said heating conductors and an insertion in said sounding chamber adapted to
- 10 tune said sounding chamber in conformity with the action of the heating wires.
- 15 2. In a thermic telephone, a sounding chamber, having a sound opening, heating conductors in said sounding chamber, a support for said heating conductors and an exchangeable insertion in said sounding chamber adapted to tune said sounding chamber in conformity with the action of the heating wires.
- 20 3. In a thermic telephone, a sounding chamber, having a sound opening, heating conductors in said sounding chamber, a support for said heating conductors and an insertion made of a good conductor of heat in
- 25 said sounding chamber said insertion being adapted to tune said sounding chamber in conformity with the action of the heating wires.
- 30 4. In a thermic telephone, a sounding chamber, having a sound opening, heating conductors in said sounding chamber, a support for said heating conductors and an insertion widened at the top in said sounding chamber said insertion being adapted to
- 35 tune said sounding chamber in conformity with the action of the heating wires.
- 40 5. In a thermic telephone, a sounding chamber, having a sound opening, heating conductors in said sounding chamber, a support for said heating conductors and an insertion in said sounding chamber adapted to tune said sounding chamber in conformity with the action of the heating wires, said insertion being arranged in front of the
- 45 sound opening in said sounding chamber.
6. In a thermic telephone, a sounding chamber, having a sound opening, heating

conductors in said sounding chamber, a support for said heating conductors and an insertion widened at the top in said sounding chamber said insertion being adapted to tune said sounding chamber in conformity with the action of the heating wires, and grooves for the passage of the sound waves at the top of said widened part of said insertion. 55

7. In a thermic telephone, a sounding chamber, having a sound opening, heating conductors in said sounding chamber, a support for said heating conductors and an insertion widened at the top in said sounding chamber said insertion being adapted to tune said sounding chamber in conformity with the action of the heating wires, and radial grooves for the passage of the sound 60 waves at the top of said widened part of said insertion. 65

8. In a thermic telephone, a sounding chamber, having a sound opening, heating conductors in said sounding chamber, a support for said heating conductors and an insertion in said sounding chamber adapted to tune said sounding chamber in conformity with the action of the heating wires, said insertion being arranged between the top 70 of said sounding chamber and said support 75 for the heating conductors in the manner of a stay.

9. In a thermic telephone, a sounding chamber, having a sound opening, heating 80 conductors in said sounding chamber, a support for said heating conductors and an insertion in said sounding chamber adapted to tune said sounding chamber in conformity with the action of the heating wires, said 85 insertion being arranged between the top of said sounding chamber and said support for the heating conductors in the manner of a stay and means for exerting pressure on said support and said insertion. 90

In testimony whereof, we have signed this specification.

PIETER DE LANGE.

ROBERT AERNOUT BARON VAN LYNDEN.
